(57) **CLAIM**

The ornamental design for a lighting fixture, as shown and described.

DESCRIPTION

FIG. 1 is a bottom perspective view of a lighting fixture showing our new design;

FIG. 2 is a bottom plan view thereof;

FIG. 3 is an enlarged fragmentary bottom perspective view thereof showing the portion of the lighting fixture indicated by lines 3-3 in FIG. 1;

FIG. 4 is an enlarged fragmentary bottom plan view thereof showing the portion of the lighting fixture indicated by lines 4-4 in FIG. 2;

FIG. 5 is an enlarged top plan view of the portion of the lighting fixture shown in FIGS. 3 and 4;

FIG. 6 is an enlarged front elevational view of the portion of the lighting fixture shown in FIGS. 3 and 4, the rear being a mirror image;

FIG. 7 is an enlarged left side elevational view of the portion of the lighting fixture shown in FIGS. 3 and 4; and,

FIG. 8 is an enlarged left side elevational view of the portion of the lighting fixture shown in FIGS. 3 and 4.

The broken line representation of hangers for the lighting fixture and the extensions of the lighting fixture are for illustrative purposes only and form no part of the claimed design. The broken line representations of the extensions of the lighting fixture are broken away to indicate that the lighting fixture can be extended indefinitely in different directions. The straight sections of the lighting fixture are broken away to indicate that the straight sections can have an indefinite length. The top of the lighting fixture is shown in FIG. 5 entirely in broken lines; the top forms no part of the claimed design.
